Primary Examiner—Caron Veynar*Assistant Examiner*—George D Kirschbaum(74) *Attorney, Agent, or Firm*—Kirk A. Buhler; Buhler & Associates(57) **CLAIM**

The ornamental design of a warning light lens, as shown and described.

DESCRIPTION

FIG. 1 is a top perspective view for a warning light lens showing my new design;

FIG. 2 is a top view thereof;

FIG. 3 is a right view, the opposite left side is a mirror image thereof;

FIG. 4 is a bottom view thereof;

FIG. 5 is a front view, the opposite back side is a mirror image thereof;

FIG. 6 is a cross-sectional view taken along the lines 6—6 from FIG. 2; and,

FIG. 7 is a cross-sectional view taken along the lines 7—7 from FIG. 3.

FIG. 8 is a perspective view of the warning light lens with environmental mounted hardware.

The broken lines in FIG. 8 depict environmental subject matter of mounting hardware for the invention only and form no part of the claimed design.
